UNITED STATES PATENT OFFICE.

EDWARD F. POOLEY, OF PHILADELPHIA, PENNSYLVANIA, ASSIGNOR TO THOMAS A. EDISON, INCORPORATED, OF WEST ORANGE, NEW JERSEY, A CORPORATION OF NEW JERSEY.

DESIGN FOR A CABINET.

41,733.

Specification for Design.

Patented Aug. 29, 1911.

Application filed June 3, 1911. Serial No. 631,198. Term of patent 14 years.

To all whom it may concern:

Be it known that I, EDWARD F. POOLEY, a citizen of the United States, residing at Philadelphia, in the county of Philadelphia and State of Pennsylvania, have invented a new, original, and ornamental Design for Cabinets, of which the following is a specification, reference being had to the accompanying drawing, forming a part thereof.

The figure is a perspective view of a cabinet showing my new design.

I claim:

The ornamental design for a cabinet as shown.

EDWARD F. POOLEY.
